ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

PICKER-CHECK FOR LOOMS.

1,119,764.

Specification of Letters Patent.

Patented Dec. 1, 1914.

Application filed December 2, 1913. Serial No. 804,277.

To all whom it may concern:

Be it known that I, ALONZO E. RHOADES, a citizen of the United States, residing at Hopedale, county of Worcester, and State of Massachusetts, have invented an Improvement in Picker-Checks for Looms, of which the following description, in connection with the accompanying drawings, is a specification, like letters on the drawings representing like parts.

The invention to be hereinafter described relates to picker checks for looms, and has for its object the production of a simple and efficient means for checking the movement of the shuttle picking mechanism.

In the preferred form of the invention, a picker check is constructed to act upon each picker stick and to be bodily moved by it in opposition to movement restraining means as the picker stick approaches each end of its stroke, the parts being so arranged and disposed that the excessive wear and injury so common in this general class of devices are avoided,—all as will best be made clear from the following description and accompanying drawings of one form of means for carrying the invention into practical effect.

In the drawings:—Figure 1 is a front view of sufficient parts at one side of a loom to show the present invention and its association therewith; Fig. 2 is a section on the line 2—2 of Fig. 1; and Fig. 3 is a section on the line 3—3, Fig. 2.

The present invention may be employed with any character of loom wherein the shuttle is thrown through the shed by a picker and picker stick, but in the present exploitation of the invention it is shown as used in a loom of the “filling replenishing” type, wherein the lay 1 has the usual shuttle boxes, that illustrated in the drawing being at the detecting end of the lay and provided with an opening 2 in the front wall through which suitable feeler mechanism may enter to feel for the filling 4 in the shuttle 5 when the latter is in said box, but these details form no essential part of the present invention. The picker stick 6 carrying the picker 7 to act upon the shuttle, and the means for operating the picker stick may be as usual, and being well understood by those skilled in the art, further description and illustration thereof are unnecessary. As the picker

stick moves from its full to its dotted line position under action of its operating mechanism in “picking” the shuttle, it is desirable that it be properly brought to rest; and, similarly, as it returns to its full line position under the impact of the incoming shuttle, it is desirable that its movement be checked with the parts in proper relative positions, as well understood by those familiar with this class of machines. Means have heretofore been proposed in an attempt to secure these ends, and in some instances leather straps have been employed to act upon the picker sticks, but in all such cases the straps have been so arranged and related to the picker sticks that serious objections have been introduced in the use of such straps, and in some instances the excessive wear and injury thereto have necessitated frequent renewal and loss of loom output. With these and other facts in view, the present invention contemplates means whereby straps of suitable material may be employed to act individually upon the picker sticks and check the movement of each as it approaches the end of its stroke in either direction and at the same time overcome the defects and objections incident to prior devices of this general type. As one means to these ends, each picker stick is provided with a check strap movable bodily with the picker stick as it approaches each end of its stroke, said strap being under the influence of movement obstructing or retarding means, the construction being such that the strap may, by its retarded bodily movement, bring the picker stick to rest in proper position without chafing action between the picker stick and strap, as will more fully appear.

Inasmuch as the picker checks at each end of the lay may be substantially the same, or varied only as associated parts may dictate, a description of one will be sufficient to make clear the essentials of the invention.

Secured to the end portion of the lay in separated relation are strap supporting brackets. These may be substantially alike and comprise a shank 10, Figs. 1 and 3, secured to the lay by suitable means, such as the bolts 9, one bracket being preferably secured to the front and the other to the back of the lay below the shuttle box, the essential in this respect being that a space may be

2 provided between the brackets for movement of the picker stick.

At its lower portion the shank of each bracket is provided with a head 11, and depending from the head of each bracket is an elongated strap bearing 12 having suitable strap supporting means at its lower portion, as the flange 13, Figs. 1 and 3.

Mounted in the brackets below the head 11 is an endless strap 14, inclosing the picker stick, and of a length from end to end that the picker stick will engage the end portions 15, 15 of the strap as the picker stick approaches the limit of its movement in each direction.

Depending from the head 11 of each bracket are the studs 16, 16, which afford suitable supports for the shoes 17, 17, two of which are preferably employed in connection with each bracket, as indicated in Figs. 1 and 2. These shoes have bearing portions 18, 18, through which the studs 16, 16 pass, and the parts are maintained in assembled relation as indicated in Figs. 1 and 2, by suitable means, such as the washers 19 and cotter pins 20, Fig. 1, the shoes being thus approximately supported below the heads 11 with their free end portions extending in opposite directions toward the ends 21, 21, of the elongated strap bearing 12. In the form of the invention shown the shoes 17 have their free end portions substantially adjacent the ends 21, 21, of the elongated strap bearing 12, but in this and other respects the construction and arrangement may be varied within the true scope of the actual invention, as defined by the claims.

The shoes 17, 17, are preferably provided with somewhat curved friction faces 22, 22, adapted to bear upon one surface of the endless strap 14 and are forced into appropriate contact with said surface of the endless strap by a yielding means.

As a simple and convenient form of means for yieldingly forcing the oppositely-extending shoes upon the surface of the endless strap, each shoe is provided with a socketed heel portion 23 for the reception of a spring 24, one end of which finds a seat in the bottom of the socketed heel portion of one shoe and the other end preferably upon a spring tension adjusting device carried by the socketed heel portion of the other shoe.

In the present form of the invention, the spring adjusting device comprises a stem 25 threaded into the outer heel portion of one shoe, substantially as indicated in Fig. 2, said threaded stem preferably carrying a spring seat 26 having a head 27, by which it may be adjusted to vary the tension of the spring. When the screw stem 25 has been adjusted to impart to the spring 24 the desired tension, the parts are retained in adjusted position by a lock nut 28.

Since the picker stick 6 swings from a

center below the lay, it will take oppositely inclined positions, as it reaches the outer and inner end of its stroke, substantially as indicated by dotted lines in Fig. 1. It is desirable, however, that the picker check strap 14 shall have an appropriate square bearing upon the outer face of the picker stick in either position of the picker stick, and to this end the present invention contemplates making the strap bearing 12, Fig. 3, of greater depth than the width of the endless strap 14, so that as the picker stick moves from one to its other position, the endless strap 14 will not only be moved bodily with the picker stick, but will be permitted to assume a proper inclination in the strap bearings to maintain a square contact between the outer face of the picker stick and the end of the strap in either position of the picker stick.

From the construction hereinbefore described as one convenient embodiment of the present invention, it will be noted that the endless strap 14 is sustained at each side of the path of the picker stick in such manner as to permit the strap to be moved bodily with the picker stick as the latter approaches either end of its stroke, and it will be further noted that by reason of this bodily movement of the entire strap 14 in its two bearing supports, all chafing or undue wear between the picker stick and the strap, as the former moves the latter, is obviated. By providing the two similar bearing supports for the endless strap at each side of the path of picker stick movement, and by properly adjusting the movement-resisting device or shoes 17 to equalize the frictional action of the shoes upon both runs of the belt, it will be seen that both runs of the belt, that is, those portions engaged by the bearing devices, will be moved through the said devices substantially equal amounts as the picker stick approaches either end of its stroke, thus doing away with all chafing action of the picker stick upon the belt, as would be the case if the two runs of the belt were not permitted such equal movements. It will also be seen from the construction described that the shoes 17 preferably act upon an extended area of the strap surface and by their curved contacting faces, obviate the excessive wear upon the belt at these points, and by permitting the belt to tilt, substantially as indicated by full and dotted lines, Fig. 1, as the picker stick approaches either end of its stroke, a true bearing is afforded the ends 15 of the strap upon the picker stick throughout the width of the belt.

Obviously, changes may be made in the relation and form of the parts, but the construction described has been found to be a good, practical form of the invention, although the invention is not necessarily re-

stricted thereto, but is definitely set forth by the claims.

What is claimed is:

1. In a picker check for looms, the combination of a picker and picker stick, an endless belt adapted to be bodily moved equally throughout by the picker stick as it approaches the end of its stroke and to be tilted in opposite directions by the picker stick as it moves toward the end of its respective strokes to present a full bearing portion of the strap to the picker stick, and means opposing the bodily movement of the endless belt. 70
- 15 2. In a picker check for looms, the combination of a picker and picker stick, an endless belt embracing the picker stick and adapted to be engaged throughout its width and bodily moved by the picker stick as the latter approaches either end of its stroke and maintain such engagement throughout its width unchanged during the continued bodily movement of the endless belt and picker stick. 75
- 20 3. In a picker check for looms, the combination of a picker and picker stick, an endless belt embracing the picker stick and adapted to be engaged throughout its width and bodily moved by the picker stick as the latter approaches either end of its stroke and maintain such engagement unchanged during the continued bodily movement of the endless belt and picker stick, and yielding means acting upon both runs of the endless belt to retard its bodily movement. 80
- 25 4. In a picker check for looms, the combination of a picker and picker stick, an endless belt embracing said picker stick and adapted to be bodily moved equally throughout by the same picker stick as it approaches the end of its stroke in either direction and yielding means acting equally on each run of the endless belt and opposing the bodily movement of the endless belt in either direction. 85
- 30 5. In a picker check for looms, the combination of a picker and picker stick, an endless belt embracing the picker stick and adapted to be engaged by the picker stick on its stroke in either direction, bearing supports for the endless belt at each side of the path of picker stick movement permitting both side portions of the endless belt to be tilted to conform to the engaging surface of the picker and moved equal amounts by the picker stick as it approaches the end of its stroke in either direction and maintain the engagement of the picker stick and belt unchanged. 90
- 35 6. In a picker check for looms, a picker and picker stick, an endless belt embracing the picker stick and adapted to be engaged by the picker stick as it approaches the end of its stroke in either direction, brackets having belt bearing portions, shoes pivot-
- ally mounted on the brackets and bearing against the belt at each side of the path of picker stick movement, and means acting yieldingly upon the shoes to retard bodily movement of the endless belt. 95
- 40 7. In a picker check for looms, a picker and picker stick, an endless belt embracing the picker stick and adapted to be bodily moved equally throughout by the same picker stick as it approaches the end of its stroke in either direction, brackets supporting the endless strap at opposite sides of the path of picker stick movement to permit the strap to tilt and present a full bearing surface to the picker stick at each end of its movement, means for applying the same movement resisting action to both runs of the endless strap at opposite sides of the path of picker stick movement to cause both runs of the belt to move like amounts under the action of the picker stick. 100
- 45 8. In a picker check for looms, a picker and picker stick, an endless belt embracing the picker stick and adapted to be bodily moved equally throughout by the same picker stick as it approaches the end of its stroke in either direction, brackets loosely supporting the endless strap at opposite sides of the path of picker stick movement to permit the strap to tilt and present a full bearing surface to the picker stick at each end of its movement, means for applying the same movement resisting action to both runs of the endless strap at opposite sides of the path of picker stick movement to cause both runs of the belt to move like amounts under the action of the picker stick. 105
- 50 9. In a loom, the combination of a picker and picker stick, an endless belt of less length than the full stroke of the picker stick, means for supporting the belt for engagement by the picker stick as it approaches the end of its stroke in either direction and permitting the belt to tilt in opposite directions to present a full bearing face to the picker stick as it moves to and reaches the end of its stroke in either direction, and means for insuring equal movements of both runs of the endless belt to prevent chafing of the belt upon the picker stick as the former is moved by the latter. 110
- 55 10. In a loom, the combination of a picker and picker stick, an endless belt, means for supporting the endless belt so that its length between portions that are to be engaged by the picker stick shall be less than the full stroke of the picker stick to permit the latter to engage the belt as it approaches the end of its stroke in either direction, and means including oppositely extending bearing shoes to engage the belt for insuring equal movements of both runs of the endless belt as the latter is moved by the picker stick to prevent chafing of the belt upon the picker stick. 115
- 60 11. In a loom, the combination of a picker and picker stick, an endless belt adapted 120
- 65 12. In a loom, the combination of a picker and picker stick, an endless belt adapted 125

to have portions engaged by the picker stick as the latter approaches the end of its stroke, brackets supporting the endless belt on opposite sides of the path of picker stick movement, shoes pivotally mounted on the brackets and having curved surfaces for engaging the belt, and means for forcing the shoes against the belt.

12. In a loom, the combination of a picker and picker stick, an endless belt adapted to have portions engaged by the picker stick as the latter approaches the end of its stroke, brackets supporting the endless belt on opposite sides of the path of picker stick movement, a pair of shoes mounted on each bracket, and a spring acting on the shoes to force them against the belt.

13. In a loom, the combination of a picker and picker stick, an endless belt adapted to have portions engaged by the picker stick as the latter approaches the end of its stroke, brackets supporting the endless belt on opposite sides of the path of picker stick movement, a pair of shoes pivotally mounted on each bracket and having heel portions,

and a spring acting against the heel portions to force the shoes against the belt.

14. In a picker check for looms, the combination of a picker and picker stick, an endless belt adapted to have portions engaged by the picker stick as the latter approaches the end of its stroke in either direction, brackets for supporting both runs of the endless belt and having a belt bearing portion, a pair of shoes pivotally mounted on each bracket with their free ends extending in opposite directions, a spring for forcing the shoes against the belt, and means for equalizing the action of the shoes of each bracket upon the belt to insure equal movements of both runs of the endless belt as the belt is moved by the picker stick.

In testimony whereof, I have signed my name to this specification, in the presence of two subscribing witnesses.

ALONZO E. RHOADES.
